UNITED STATES PATENT OFFICE.

MILTON G. CLYMER AND ARTHUR E. RITCHIEY, OF ST. LOUIS, MISSOURI; SAID RITCHIEY
ASSIGNOR OF HIS RIGHT TO ANDREW B. REMICK, OF ST. LOUIS, MISSOURI.

METHOD OF OPENING AND REFINISHING CANS.

Original application filed June 12, 1918, Serial No. 239,624. Divided and this application filed February 26, 1919, Serial No. 279,354.

To all whom it may concern:

Be it known that we, MILTON G. CLYMER and ARTHUR E. RITCHIEY, both citizens of the United States, and residing at St. Louis, 5 in the State of Missouri, have invented a certain new and useful Improvement in Methods of Opening and Refinishing Cans, of which the following is a specification.

This invention relates to a method of opening and refinishing cans. This application is a division of application Serial Number 239,624, filed June 12, 1918.

Many commodities, such as canned fruits, are packed and shipped in cans, and in establishments manufacturing preserves, large numbers of these cans must daily be opened to utilize the contents thereof. Now this not only requires considerable labor, but the open cans, when opened by the present 20 methods and mechanisms employed, are unfit for further use, and must, therefore, be discarded and sold for junk, even though these cans may be in excellent condition and can readily be utilized. Furthermore, the cans, 25 on account of being shipped, are often bent and dented considerably so as to not only prevent their being effectively opened, but also used again.

One of the objects of this invention, therefore, is to provide a method of opening and refinishing cans whereby the edge of the can is refinished and contoured so as to permit its subsequent use.

Another object of this invention is to provide a method for opening and refinishing cans whereby the edge will not only be refinished and contoured, but also provided with a rim.

Further objects will appear from the detail description taken in connection with the accompanying drawing which describe and illustrate one embodiment of a method and an apparatus for carrying out the method. In the drawing,

45 Figure 1 is a vertical section taken through a part of an apparatus or machine whereby this method may be carried out;

Figure 2 is a detail of Figure 1, showing the operation of the mechanism in carrying 50 out the method;

Figure 3 is a detail of a can end, showing the ordinary top in position;

Figure 4 is a view similar to Figure 3, showing the head partially cut out of the can;

Figure 5 is a plan of Figure 4;

Figure 6 is a view similar to Figures 3 and 4, but showing the head completely severed, the edge completely refinished and the rim positioned thereover; and

Figure 7 is a view similar to Figure 6, but showing the rim in final attached position and the cover in place.

Figure 3 shows an ordinary can comprising a can body O having a head H attached to the can by the usual overhanging seam C. This can is of a type usually employed for storing commodities, such as fruits and preserves, the head being firmly attached to the can to form a sealed joint. Such a can is ordinarily opened by cutting the head along the edge of the can, but this leaves a rough and uneven edge, which if it is ragged will be wavy so that the can is unfit for further service as a container for storing commodities.

In accordance with this invention, the head of the can is cut closely to and along the edge of the can body, while the can edge is being supported along but outside of the line of cut; the inwardly projecting lip is, however, pressed against the can body while the outside of the can is being supported along the line of cut; the can edge is also contoured externally to shape it; a rim is now positioned on the cut edge of the can so as to give a finished appearance.

The mechanism for carrying out this method may be varied, keeping in mind the essential features. Mechanism for carrying out this method is shown in Figures 1 and 2 and comprises a head 26 mounted on a suitable shank for attachment to suitable operating mechanism, although the shank may form a handle for manual operation.

The head comprises an annular guide 28 which flares at its lower end as shown at 29, to take over the can. Arranged inside of this head is a cutter 30, which has a serrated cutting edge 31, adapted to cut the head of the can. It will be noted that the cutter is spaced from the guide, and that the annular recess between the cutter and the guide extends beyond and past the ter-

mination of the cutting edge of the cutter, as shown at 32, for a purpose hereinafter to be described.

The head may either be forced on the can head or the can may be forced into the head; whatever form of relative movement is used, the can will be caused to enter the flaring guide 28-29 and move therein until the head of the can is engaged by 5 a serrated edge 31 of the cutter 30, which will cause the cutter to cut the can head along and at a definite and predetermined distance from the outer edge of the can. During the first part of the movement, the 10 cutter will puncture the can head at numerous points, and cut along the edge until the head is completely severed. Thereafter, further movement will cause the cut can edge and the rim to enter the space 32, between the cutter and the guide, so as to 15 force the rim therein, and press the cut edge against the inside face of the can body, as shown in Figure 2. This action will currently straighten out the bent edge of 20 a can, and contour the rim so as to make the finished edge a perfect circle, with both the outside and the inside edges of the rim refinished. When the head 26 and the can are again moved out of cooperative relation 25 30 the can head which is now loose in the can, can be taken out and the contents can be discharged.

Figures 3 to 7 inclusive illustrate more fully the method employed, of cutting and 35 refinish the can. In Figures 4 and 5, the head H of the can has been partially cut by the serrated cutting edge 31, as shown at A, and the cut edge has been partially bent against the inside face of the can body. 40 Figure 6 shows the cut edge B completely pressed against the inside face of the can body O, and it will be noted that in view of the fact that this action takes place while the can is engaged on the outside by the 45 guide, and while the can is thus supported, the edge B is pressed uniformly around and against the face of the can body, so as to form a completely refinished inside edge. Concurrently, the outer edge of the can, 50 that is, the folded over part D of the head rim, has been refinished and contoured and made perfectly circular by the engagement of the inside face of the guide therewith. Accordingly, both the inside and outside 55 faces of the rim have been refinished, and this finish is smooth, on account of the wiping action of the cutter and of the guide. There is thus provided a smooth circular rim which is refinished on both its outside 60 and its inside faces.

In order to provide a rim which can be readily closed by a cover, a formed rim E, having a finished inside face F, is placed over the refinished rim of the can, and the 65 outer flange G is folded over the can, or in

any suitable manner, so as to make a firm attachment thereto. This can be done in any suitable manner. The can is thus provided with a finished rim which can receive a suitable cover 1.

It will thus be seen that the invention accomplishes its objects. The method employed is simple and effective and produces from a can which would ordinarily be junked, one which can be used again for 70 the storing and shipping of commodities. It is to be noted that not only is the can edge supported along, but outside of the line of cut while the cutting takes place, but this support is maintained during the pressing 75 or refinishing operation by a firm inward pressure, resulting not only in a seamed refinishing and burnishing of the edge, but also in conforming or contouring the can edge to a perfect circle, burnishing even 80 the outside seam so that the rim seam can be closely conformed to the can and produce, in effect, a sealed structure.

While one form of mechanism has been described, it is to be understood that this 90 method is not necessarily dependent upon any particular mechanism, but that the mechanism may be varied without departing from the spirit of this invention. It is, therefore, to be understood that this invention is not to be limited to the specific 95 details shown and described.

Having thus described the invention, what is claimed is:

1. The method of opening and refinishing 100 cans, comprising, cutting the head of the can along and inside of its edge while the edge is being supported against distortion for an extended part therealong but outside of the line of cut, and refinishing the 105 cut edge.

2. The method of opening and refinishing cans, comprising, cutting the head of the can along its edge, contouring the outside 110 edge to the desired shape, and refinishing the cut edge.

3. The method of opening and refinishing cans, comprising, cutting the head of the can along its edge, and pressing the cut edge against the body of the can while the outside 115 of the can is being supported against distortion for an extended part along the line of cut.

4. The method of opening and refinishing cans, comprising, cutting the head of the 120 can along its edge, and pressing the cut edge against the body of the can while its outside edge is supported against distortion for an extended part therealong.

5. The method of opening and refinishing 125 cans, comprising, cutting the head of the can along its edge, contouring its outside edge to the desired shape, and pressing the cut edge against the body of the can.

6. The method of opening and refinishing 130

cans, comprising, cutting the head of the can along its edge, contouring its outside edge to the desired shape, and pressing the cut edge against the body of the can while 5 its outside edge is being contoured.

7. The method of opening and refinishing cans, comprising, cutting the head of the can along its edge, and refinishing the outside and inside edges of the can while being 10 supported for an extended part therealong against distortion.

8. The method of opening and refinishing cans, comprising, cutting the head of the can along its edge, refinishing the cut edge, 15 and placing a rim on the refinished edge.

9. The method of opening and refinishing cans, comprising, cutting the head of the can along its edge, refinishing the outside and inside edges of the can, and placing a 20 rim on the refinished edges.

10. The method of opening and refinishing cans, comprising, cutting the head of the can along its edge, contouring its outside edge, pressing the cut edge against the body 25 of the can while its outside edge is being contoured, and placing a rim on the refinished edges.

11. The method of opening and refinishing cans, comprising, cutting the head of the can along and inside of its edge while the 30 entire outer edge of the can body is supported, and refinishing the cut edge.

12. The method of opening and refinishing cans, comprising, cutting the head of the can along and inside of its edge, and reshaping 35 the cut portion while the entire outer edge of the can body is supported.

13. The method of opening and refinishing cans, comprising, cutting the head of the can along and inside of its edge while the 40 entire outer edge of the can body is supported, and pressing the cut portion outwardly against the can body.

14. The method of opening and refinishing cans, comprising, cutting the head of the 45 can along and inside of its edge while the entire outer edge of the can body is supported, and contouring the can edge in accordance with such support.

In testimony whereof we affix our signatures this 24th day of December, 1918.

MILTON G. CLYMER.
ARTHUR E. RITCHIEY.
